UNITED STATES PATENT OFFICE.

JOHN GILSON, OF PORT WASHINGTON, WISCONSIN.

DESIGN FOR A CHAIR-SPINDLE.

SPECIFICATION forming part of Design No. 31,416, dated August 15, 1899.

Application filed July 20, 1899. Serial No. 724,561. Term of patent 14 years.

To all whom it may concern:

Be it known that I, JOHN GILSON, a citizen of the United States, residing at Port Washington, in the county of Ozaukee and State of Wisconsin, have invented and produced a new and original Design for a Chair-Spindle; and I do hereby declare the following to be a full, clear, and exact description of the same, reference being had to the accompanying drawings, forming a part thereof.

In the said drawings, Figure 1 is a side elevation; Fig. 2, a partly-sectional view of the upper part, and Fig. 3 a plan view of a chair-spindle embodying my new design.

My design relates to the new and original shape or configuration of the article.

The leading or essential feature consists in the unitary design for a chair-spindle made the subject of illustration, comprising the shape of the cylindrical body A of the same diameter from top to bottom and of a continuous spirally-threaded external configura-

tion interrupted in a single continuous vertical plane by a parallel-walled groove B extending all the way from top to bottom, with a central vertical annular smooth-walled bore C, a flat horizontal top D, and a nearly-flat bottom E, slightly rounded at its annular edge.

Minor features of said design include a horizontal annular smooth-walled opening F, communicating with a horizontal annular opening G of less diameter and formed with spirally-corrugated walls.

Having thus described my invention, what I claim as new, and desire to secure by Letters Patent, is—

The design for a chair-spindle, substantially as herein shown and described.

In testimony whereof I affix my signature in presence of two witnesses.

JOHN GILSON.
